UNITED STATES PATENT OFFICE.

JOHN A. HOLMBERG AND FRANCIS H. DUNCAN, OF KANSAS CITY, MISSOURI.

DESIGN FOR A CHIMNEY COWL OR CAP.

SPECIFICATION forming part of Design No. 30,284, dated February 28, 1899.

Application filed January 30, 1899. Serial No. 703,904. Term of patent 14 years.

To all whom it may concern:

Be it known that we, JOHN A. HOLMBERG and FRANCIS H. DUNCAN, of Kansas City, Jackson county, Missouri, have invented and 5 produced a new and original Design for Chimney Cowl or Caps, of which the following is a specification, reference being had to the accompanying drawings, forming part thereof.

Our invention relates to a new and useful 10 design for chimney cowls or caps.

In the accompanying drawings, Figure 1 represents a perspective view, and Fig. 2 a central vertical section, of a chimney cowl or cap, showing our new design, and the leading 15 or material feature of the same resides in the rectangular neck, with the annular base-flange projecting outward from said neck and the rectangular cap supported above said rectangular neck with an intervening space by 20 means of vertical arms.

Minor features of our design are embraced 25 in the peak shape of the cap, the depending flanges at the sides and ends of the cap, the arms extending vertically from the sides and ends of the neck to the said flanges of the cap, and the downward-flaring formation of the base-flange and the angle-flanges depending vertically from the corners of said base-flange.

Referring to the drawings in detail, 1 designates the rectangular neck. 30

2 designates the annular downwardly-flaring base-flange.

3 designates the vertically-depend ing corner-flanges of the base-flange. 35

4 designates the peak-shaped cap.

5 designates the vertically-depend ing side and end flanges of the peak-shaped cap.

6 designates the vertical arms extending from the neck to the flanges of the cap. 40

What we claim is—

The design for a chimney cowl or cap, as herein shown and described.

In testimony whereof we affix our signatures in the presence of two witnesses.

JOHN A. HOLMBERG.
FRANCIS H. DUNCAN.
